CYLINDRICAL DRINKING FOUNTAIN

Allen C. Wright, Moraga, Calif., assignor to Haws
Drinking Fountain Company, Berkeley, Calif.
Filed Nov. 30, 1970, Ser. No. 26,231

Term of patent 14 years

Int. Cl. D23—01

U.S. Cl. D67—4

FIG. 1

FIG. 2

FIG. 3

FIG. 4

FIG. 5

FIG. 1 is a perspective view of a cylindrical drinking fountain looking downwardly toward the top thereof.

FIG. 2 is a top plan view of the fountain.

FIG. 3 is a front view in elevation of the fountain.

FIG. 4 is a side view in elevation thereof.

FIG. 5 is a rear view in elevation of the fountain.

I claim:

The ornamental design for a cylindrical drinking fountain, substantially as shown.
